Application February 19, 1938, Serial No. 191,493

7 Claims. (Cl. 91—70.1)

This invention relates to the manufacture of incandescent lamps and particularly to the art of providing lamp bulbs upon a selected or predetermined area with a metallic reflecting coating, such as silver, in order to reflect and direct the light of the lamp efficiently into the desired field.

The invention consists in a novel process of applying a continuous and permanently adherent metallic coating to the inside of an evacuated bulb under conditions which permit the use of automatic or semi-automatic equipment at low labor cost and in such manner as to minimize the loss of silver in the process. The invention also includes within its scope the novel apparatus herein shown as employed in the practice of the process of our invention.

Metallic coatings have been heretofore applied to lamp bulbs and to radio tubes under somewhat different conditions and with somewhat different objects than those contemplated by the present invention. For example, in the production of electronic tubes it has been customary to evaporate a small piece of magnesium or aluminum as a getter in the finished tube, after evacuation and as the tube is being sealed off and while the glass walls are still hot from that process. The amount of metal so volatilized as a getter has always been considerably in excess over that required to combine with the oxygen present in the tube and this excess condenses on the inner walls of the tube in a bright or dark coating. The method used to evaporate the getter depends upon the particular substance chosen and the choice of location in the tube. When the getter is readily volatile a gas flame impinging on the tube is sufficient to evaporate it. Sometimes a getter is vaporized as a bead on a tungsten resistance wire or as a small piece of metal placed in a high frequency field.

In carrying out our improved process of producing a reflecting coating on the inside of a lamp bulb by the evaporation within the bulb of a metal or alloy, we are able to employ with advantage either the resistance heating or the high frequency heating steps above referred to.

Before proceeding to a detailed description of our process and apparatus, it will be convenient to discuss briefly some of the problems with which we are concerned and to indicate the solution achieved by our invention.

When silver and certain other metals or alloys are melted in air, small quantities of air, chiefly oxygen, dissolve into the molten metal and most of this oxygen is subsequently evolved when the

metal is subjected to changes in temperature or pressure. The mechanism of this phenomenon is not completely understood, but in the case of silver it is probably due to the formation of silver oxide which dissolves in the molten silver, but which decomposes with the evolution of oxygen at a temperature near the melting point. When this oxygen is evolved the molten silver spits and sputters. We have found that a pellet of silver suitable for coating a bulb ordinarily contains sufficient adsorbed gas to sputter in vacuo if it is rapidly heated above its melting point and near its boiling point. This sputtering must be avoided if uniform coatings are to be formed on the reflecting surface of the lamp bulb.

Silver that has been fused and allowed to cool in a vacuum or in an inert gas atmosphere does not absorb oxygen and therefore does not sputter even when heated rapidly in a vacuum. However, in silvering lamp bulbs it is convenient to employ the same boat or crucible for holding silver for coating operations on successive bulbs and it becomes necessary to introduce additional silver into the boat from time to time. Such added silver may preferably take the form of small pellets or short lengths of silver wire which always contain adsorbed gases likely to cause sputtering if heated rapidly to vaporizing temperatures. It is therefore essential to provide against sputtering at all times, particularly if automatic machinery is to be used in the process. We accomplish this important result by raising the temperature of the boat, together with its charge of silver, slowly to a temperature well above its melting point, for example at about 1100° C. and holding it at this temperature for a definite period and then abruptly raising the temperature to the vaporizing point (about 1800° C.) for a short period of time, or until the desired amount of silver has been vaporized. For small lamps—50 watts for example—the period of vaporization need not exceed a few seconds and this interval may be varied depending on the size of the bulb to be coated, on the number of boats or crucibles of silver placed within the bulb, and on the amount of current passing through the heating element. However, the length of time that the higher or flashing voltage must be effective is not only critical, but must be varied depending on the size of the bulb being silvered and upon other factors. In silvering the bulb of a 50 watt lamp the preliminary interval at which the silver is maintained in a molten condition may be from ten to twenty seconds, while the flashing period must be restricted to about six seconds to vapor-

ize the desired amount of degassed silver. It is desirable under some conditions to vaporize the silver as rapidly as possible in order to obtain a brilliant coating. While the desired amount of silver may be vaporized at a slower rate, the coating tends to take a whitish color under such conditions, probably due to the individual crystals of silver having time to reach appreciable size. A fine crystalline deposit is essential if a brilliant coating is desired.

The thinner the coating of silver and the more rapidly it is applied to the glass of the bulb, the more nearly amorphous and therefore the brighter is the reflecting coating provided. On the other hand when the silver coating is allowed to become of relatively coarse crystalline structure the light reflected thereby is of a bluish tinge. A coarse crystalline area, by causing multiple reflection between the facets of the crystals with resulting selective absorption of the light rays toward the red end of the spectrum, causes the light ultimately leaving the reflecting area to have a larger percentage of blue rays than in the light leaving the filament. Therefore the light from a lamp having such a crystalline area has a less yellowish tinge than light leaving a similar lamp having a homogeneous brilliant reflecting area. This result is desirable for many uses and may be secured in practising the process of our invention by controlling the distribution of vaporized metal so that certain zones of the coating are somewhat thicker and of different crystalline form or size than others, as by employing two sources of metal for evaporation within the bulb which may overlap in a zone of the coating produced within the bulb, or by any means reducing the rate of vaporization and increasing the time.

In carrying out the process of our invention, it is desirable to heat the glass of the bulb substantially while the bulb is being evacuated and during the metal vaporizing step in order to remove adsorbed gases and water vapor from the pores of the glass and so to insure a secure and permanent bond between the metallic coating and the glass walls of the bulb. On the other hand, the sealing of the bulb must be efficient and reliable throughout the steps of the process even though portions of the bulb may be heated to an annealing temperature in the neighborhood of 400° C. Our invention accordingly contemplates the step of temporarily sealing the bulb with a cooled medium, for example, by a rubber sealing member cooled by a water-circulating system. It is important not to overheat the sealing medium to a degree which would cause its deterioration or sufficiently to cause vapor or other distillation products to be evolved therefrom and enter the bulb. We rely upon a cooling system to obviate this danger. This is supplemented, of course, by the action of the evacuating system in immediately withdrawing from the bulb any vapor which may be momentarily evolved from the sealing means.

The bulb may be heated by any convenient means during the exhausting and vaporizing steps of the process, but, as herein shown, we prefer to use an annular furnace through which bulbs may be moved successively while these steps are being carried out thereon.

Another important characteristic of our process consists in selectively directing the vapor of the vaporized metal charge to different parts of the bulb surface as required in the metallic coating. For example, in coating an inverted

bulb the metal charge may be confined so that when vaporized a portion of the vapor is directed laterally against the bulb walls and a greater portion of the vapor directed upwardly into the globular end of the bulb. The selective distribution of the metallic vapor may be further controlled by the provision of shielding devices, as for example, a shield disk arranged to limit the amount of metal vapor passing downwardly into the neck of the bulb.

An important and novel feature of the apparatus herein shown consists in a container or boat which is generally conical in shape and provided with peripheral openings for the passage of metallic vapor in a lateral direction. The shape of the boat containing the metal to be vaporized is of importance as also is its size, the materials of its construction and its position in the bulb being treated. For coating an inverted bulb as above outlined, a conical boat is advantageous because when a metal such as silver is rapidly vaporized in a vacuum, the metallic vapor occupies a volume many times that of the molten metal and in the act of escaping from the latter at a rapid rate of vaporization, the vapor expands almost with explosive violence. Thus there is a practical limit to the rate of vaporization as above explained, and this explosive force can in part be directed in any desired direction by the shape of the boat containing the molten metal.

For the purpose of controlling the rate of vaporization, adjustable resistance may be introduced into the power circuit. The resistance of the boat and its contents in the circuit is preferably arranged to be but a small part of the total resistance of the entire circuit. This has its advantages in that changes in the resistance of the boat itself, or changes due to variations in its contents, do not greatly effect the resistance of the circuit as a whole. It is desirable that such effects may be as nearly constant as possible since the resistance of the boats directly effects the amount of heat generated at that point.

In addition to the essential step of maintaining the glass of the bulb at a proper temperature, it is also imperative to have a chemically clean glass surface upon which to deposit the metallic coating. In many cases, it is desirable to subject the bulb to a preliminary cleaning with chromic, sulphuric or hydrofluoric acid solutions effecting the removal of a surface film from the inner walls of the bulb.

Another important feature of our invention consists in controllably timing the flashing interval. The preheating period required to degas a silver charge is not critical, but the vaporizing period is critical for reasons already discussed and to control the length of this period the apparatus of our invention is provided with an automatically acting switch in the heating circuit which may be adjusted in accordance with the requirements of the work in hand. In this manner we provide means for controlling the amount of silver vaporized in a bulb of any given size. By maintaining relatively constant the impressed voltage and the resistance of the boat the rate at which heat is developed and at which the metal is vaporized will be regulated and the amount of metal evolved as vapor may be controlled. In applying a silver coating to a bulb for a 50 watt lamp we find that about 0.03 gram of silver is required. If more than this amount is vaporized from the boat it tends to become lost since it is likely to settle upon the electrodes.

A more complete understanding of the invention may be had from the following description of a typical manner of putting it into practice, together with the description of one form of apparatus which may be advantageously employed and which is shown in the accompanying drawings in which,

Fig. 1 is a view in perspective of a portion of the apparatus,

Fig. 2 is a view in elevation, partly in section, of one station of the apparatus showing a bulb in position therein,

Fig. 3 is a view in elevation on an enlarged scale of container or boat for the metal to be vaporized,

Fig. 4 is a corresponding plan view of the container,

Fig. 5 is a diagrammatic view of the apparatus illustrative of the cooling system,

Fig. 6 is a view similar to Fig. 2 showing further details of construction and an alternative form of electrodes,

Fig. 7 is a diagrammatic view illustrative of the cycle of the apparatus,

Figs. 8, 9 and 10 are views in elevation illustrating alternative arrangements of electrodes and metal containing boats,

Fig. 11 is a view in perspective of the operating mechanism of the apparatus and certain circuit-breaking mechanism thereof, and

Fig. 12 is a view in elevation of the circuit-breaking mechanism.

The apparatus herein illustrated is of the turret type in its general construction and includes a flat annular ring 10 having twenty-four stations thereon, and arranged to be rotated in counter-clockwise direction and in a step-by-step manner. The mechanism for rotating the ring 10 is of secondary importance only and is suggested in Fig. 11, which shows a vertical shaft 50 to which the ring is connected and which carries a disk 51 having slots spaced about its circumference and arranged to receive consecutively a roll 52 carried on a crank 53 upon the upper end of a driven shaft 54. The ring 10 is made hollow as shown in Fig. 6 to receive cooling water and at each station it is traversed by a hollow cylindrical stud 11 which is sealed or brazed securely into the ring and projects somewhat above its upper surface.

A bulb-supporting unit is secured to the projecting end of each of the hollow studs 11 and rests upon the face of the ring 10. Each unit comprises a cylindrical body 12 recessed to receive the projecting end of the stud and having a water chamber 13 in its upper portion which is closed by a metal cover disk 14 secured permanently in place. The water chamber 13 is traversed by two or more vertical insulating tubes 15 which extend through the cover plate 14 at their upper ends and downwardly at their lower ends into the body of the unit 12 below the chamber 13. The tubes 15 serve to insulate the vertically disposed electrodes 17 which, as best shown in Fig. 2, extend through the water chamber 13 and upwardly for a considerable distance through the cover plate 14. Supported upon the cover plate 14 is a shouldered disk 16 of rubber or other solid compressible material which serves as a sealing seat for the bulb being treated and to this end it is shouldered to extend somewhat into the open neck of the inverted bulb and to provide a circular cushion and support for the end of the bulb.

As already noted it is extremely important to maintain the temperature of the sealing disk 16 below that at which deterioration may occur and

more especially below that at which any of its material may be vaporized and so impair the vacuum within the bulb or admit impurities which would interfere with a permanent bond between the metallic coating and the glass walls of the bulb. Accordingly the illustrated apparatus includes a water cooling system diagrammatically shown in Fig. 5. This system includes the hollow ring 10 and the water chamber 13 in each of the bulb-holding units. The system is supplied with cooling water by gravity from a centrally disposed reservoir 39 which, as shown in Fig. 1, is constantly supplied with cooling water by means of a feeder pipe 40. Cooling water passes from the reservoir 39 through a number of radially extending tubes 38 to one bulb-holding unit of a group of four units. Cooling water flowing through the tube 38 circulates through the chamber 13 of the first unit of this group, then passes successively through intermediate connecting tubes 41 to the cooling chambers of the other units of the group and is finally discharged to the ring 10 through a downwardly curved outlet pipe 42. The ring 10 is provided with three return ducts 43 extending inwardly from spaced points in its periphery to a common discharge pipe not shown. The effect of the cooling water circulating in this system is continuously to cool the thin cover plate 14 upon which the sealing disk 16 is supported and to cool the electrodes which pass upwardly through the disk 16, and in general, to maintain the disk 10 and the bulb-supporting units against any undue rise of temperature.

Each electrode, as shown in Fig. 2, may comprise a lower cylindrical portion 17 and an upper portion 18 of the same diameter, the two portions being adjustably connected by an enclosing sleeve 19. The effective length of the electrodes may be varied by loosening clamping screws set in the sleeve 19 and by moving the upper portions 18 of the electrodes up or down and again clamping them in position. The lower end of each electrode is connected to an outwardly extending metal arm 20 which is insulated from the body of the unit as shown in Fig. 6 and provided at its outer end with a terminal 21 for the electric heating circuit which includes the lead 22. The upper portions 18 of the electrodes are surrounded by a refractory disk 23 of aluminum or other refractory material and upon this rests a thin nickel disk 24 perforated to clear the electrodes and extending at its edge into close proximity with the neck of the bulb. The disks 23 and 24 constitute one satisfactory form of shield for preventing vaporized metal from passing downwardly and being deposited in the neck of the bulb where it is not required, and confine the vaporized metal to the bowl portion of the bulb where it is desired.

The electrodes carry between their upper ends the container or boat in which is placed the slug of silver or other metal to be vaporized. The boat comprises a resistor held between the two heavy electrodes. It acts as the crucible or boat holding the charge of metal to be vaporized, by its resistance to the passage of the electric current it produces the required heat, and by its shape and design it directs the vapors of the boiling metal. The size of this boat should be as small as possible so that its heat capacity will not be sufficient to prolong unduly either the heating up period or the cooling period, and it should have a capacity of perhaps two- or three-tenths of a gram of silver. It must be made of a highly refractory material, that is, an electrical

conductor such as tungsten or molybdenum. Its general shape should be conical with the apex of the cone downwards, or of any other shape with side wall flaring to an enlarged opening at the top. This is necessary since the vapors leave the boat at the time of vaporization in an almost explosive manner, and it is desired that most of these vapors flash upwards so as to coat the large surface of the globular portion of the bulb. However, it is essential that some smaller part of the vapors strike the side walls of the bulb, in the vicinity of the boat, and that a still smaller amount pass down into the neck of the bulb. Since these vapors occupy a definite space and since the high vacuum pump is operating during the flashing period there is a slight tendency for these vapors to pass downwards towards the neck with almost any form of boat. However, we have found that it is possible to direct and control the amount of metallic vapors that strike the side walls and the neck of the bulb by perforating the boat with small holes or small slits at the sides and at the bottom. Evaporation of the metal, during the flashing period, occurs in part through these small openings and is thereby directed towards the side walls and the neck, the bulk of the vapors leaving the flaring top of the boat and serving to coat the large surface of the globular part of the bulb. The boat herein shown comprises a heavy molybdenum wire 25, perhaps .050 inch in diameter, bent to present two vertically extending legs and an intermediate vertical coil of four or five turns converging downwardly. The molybdenum wire 25 is encircled by a coil 26 of fine tungsten wire substantially 0.0055 in diameter. In making the boat the molybdenum wire, previously wound with the tungsten wire 26, may be shaped as a conical helix, and finally a second tungsten wire 27 is wound reversely about the upper end of each leg and about the conical helix in the valley between adjacent turns. The purpose of this construction is to provide a receptacle in which the molten metal may be retained, partly mechanically and partly by capillary action, during the preliminary heating step and before vaporization takes place.

It will be noted that in general the boat has the shape of an inverted cone with a small opening in its lower end and circumferential cracks between the turns of the wire 25. These openings are of such dimensions that the molten silver is retained in the boat by capillary action, while in the flashing or vaporizing step the metallic vapor of the charge is directed quantitatively to those parts of the bulb wherein it is to be distributed, that is to say, the greater part of the charge is flashed upwardly in a divergent field to cover the globular end of the bulb. A portion of the charge is flashed laterally through the peripheral cracks of the boat against the side walls of the globular part of the bulb, and a still smaller portion of the charge is flashed downwardly toward the neck of the bulb for coating the walls above the shield disks 23 and 24.

It will be understood that the boat may be bodily adjusted vertically to locate it at the proper height for most advantageously treating bulbs of the particular shape and size in process, or, as will be explained hereinafter, two boats may be located at different levels within the bulb and a metallic charge vaporized simultaneously or successively from them in coating a large bulb or one of irregular shape.

The boat constitutes the resistance element of the heating system. It is carried by the large

electrodes 17 which have sufficient conductive capacity to carry the requisite current without the development of any substantial amount of heat. The heating of the circuit is thus concentrated in the boat and in the metal charge contained therein.

Lead wires 22 extend downwardly from the electrode terminals 21 to a pair of spring contact shoes 60 movable with the ring 10, there being one pair of shoes for each bulb-supporting unit. The individual shoes are located one above the other as shown in Fig. 1 and project rearwardly and outwardly with reference to the ring 10 and somewhat below the ring. The shoes 60 are arranged to wipe along and make electrical contact with a pair of segmental terminals 61 arranged concentric with the axis of the ring 10 and spaced from its circumference at the same height as the contact shoes 60. The terminals 61 are carried at one end by a block 62 secured to the upper end of a fixed bracket 63. They are insulated from the block 62 but connected to the wires 64 of the power circuit. The terminals 61 extend circumferentially to include two stations of the apparatus, that is to say, stations No. 13 and No. 14 as shown in the diagram of Fig. 7. Accordingly, when any pair of contact shoes 60 are moved into contact with the stationary segmental terminals 61, the heating circuit is closed through the bulb-supporting unit which has just arrived at station No. 13 and current is maintained flowing until the ring is advanced to carry that particular unit beyond station No. 14. The current supplied during this interval is sufficient to melt the silver charge contained within the boat in the bulb-supporting unit and maintain it in molten condition at a temperature of about 980° C. for a period of ten to twenty seconds, with the result that oxygen or other gases absorbed in the metal are driven off and thus the danger of sputtering is obviated, as already explained.

The segmental terminals 61 are supported at their forward ends by the block 62 and bracket 63 and at their rear ends by a similar block 65 and bracket 66. Beyond the terminals 61 is located another bracket 67 carrying an insulated block 68 having upon its inner face a pair of terminal plates 69 located one above the other at the same level as the segmental terminals 61. The terminal plates 69 are connected to leads 70 of the power circuit which is employed to flash the molten silver in the boat when the ring has been advanced to carry a bulb supporting unit to station No. 15 in the cycle of the machine. Since the period of rest of the ring between its successive steps in its rotation is longer than the interval required for flashing the metal charge, an automatic timing switch is included in the circuit with the leads 70. This mechanism is shown more or less diagrammatically in Figs. 11 and 12, to which attention is now invited. The turret operating shaft 54 is connected through bevelled gears to a horizontal shaft 55 and this in turn is connected through elliptical gears 56 to a horizontal shaft 57 which, through a pair of bevel gears, drives a cam shaft 58. The cam shaft 58 is journaled in the frame of the machine and carries a cam 59 on its right hand end as seen in Fig. 11. This cam acts to reciprocate a rod of adjustable length comprising the threaded sections 71 and 72 connected by a coupling member 73 having right and left threaded connection with the sections 71 and 72. Bearings 74 support the rod for endwise reciprocation and a spring 75 interposed between the right hand bearing and a

pin in the rod section 72 holds the rod at all times in contact with the periphery of the cam 59. At its right hand end the rod carries a head to which is connected one end of the lead 70. The head is also provided with a flat spring contact plate 76. As the rod is reciprocated the contact plate 76 makes and breaks the circuit by engaging a terminal in a fixed block 77 which is connected to a lead 78 in the power circuit.

The reciprocation of the switch rod is timed positively through the mechanism above described with relation to the intermediate movement of the ring 10 so that the power circuit through the terminal blocks 69 is made and broken while one of the bulb-supporting units is at rest in station No. 15. The interval during which this circuit is closed may be adjusted and controlled by turning the coupling member 73 to adjust the length of the switch rod and so regulating the interval of engagement between the contact plate 76 and the block 77. The circuit 70 has a substantially higher voltage impressed thereon than the power circuit 64, with the result that when the switch 76-77 is closed, sufficient current is delivered to the boat to raise the temperature of the metal therein abruptly to its vaporizing point, for example, 1800° C. for silver. The temperature is maintained for a regulated interval of six seconds or less and it is during this interval that the molten metal is vaporized or raised to the point of active ebullition and a bright metallic coating formed upon the walls of the evacuated bulb located at station No. 15.

As already intimated it is important to maintain the bulb being treated under substantial vacuum and continuously withdraw from the bulb any gas vapor evolved from the molten metal in the boat. To this end each station is connected to an exhaust system and includes a vertical tube 30 which passes upwardly through the body of the unit and opens above the rubber seal 16 in a cavity provided between the electrodes 17. At its lower end the tube 30 is sealed into the upper end of a heavy rubber tube 31 which passes out through the bottom of the ring 10 and downwardly through perforations in a pair of spaced plates 32 which are secured in position beneath the ring at each station. Between the plates 32 is mounted a shut-off valve 33 which may be closed by engagement with a stationary cam, not shown, in the rotation of the ring and at the proper point in the cycle of operations. A stationary cam is also provided for opening the shut-off valve and admitting air to the coated bulb toward the end of the cycle. The vacuum system is of the general character employed in lamp making machinery and since it forms only one element of the present invention it will not be more fully described herein. It will be understood that the arrangement of the vacuum system herein disclosed is illustrative only and may be varied as desired. The connection to the pump is indicated at 35.

Referring to the diagram of Fig. 7 it will be noted that when each unit reaches the No. 4 station the rough vacuum pump begins to operate, continuing to exhaust the bulb up to the seventh station except that at station No. 4 the bulb under treatment is tested by a leak detector which indicates whether the bulb has been improperly positioned upon its seat or if, for any other reason, a vacuum has not been formed with the bulb.

At the seventh station a high vacuum pump

comes into action and continues to exhaust the bulb up to the sixteenth station.

At the sixteenth station the shut-off valve 33 is operated to close the exhaust tube 31 with the bulb in evacuated condition. At that time the operation of flashing the silver has been completed and it remains only to cool the coated bulb gradually and without creating undue strains therein. The cooling of the bulb is effected during its movement from station No. 17 to station No. 23 and at station No. 23 the shut-off valve 33 is opened admitting atmospheric pressure to the bulb so that it may be removed from the sealing disk 16.

It is important to maintain the glass of the bulb at a high temperature during the coating operation in order to insure a permanent bond between the metal coating and the glass of the bulb, and also in order to avoid chilling the metal-containing boat within the bulb. To this end an annular oven 45 is arranged concentrically with and above the ring 10 and in such position that successive bulbs upon the bulb holding units of the ring are passed through it throughout substantially 210° of their movement in the circular path of the ring. The oven is of heat insulating material and provided with a pair of circumferentially disposed gas pipes 46 perforated so as to direct a continuous series of flames toward the bulbs in their passage through the oven. As indicated in the diagram of Fig. 7 the annular oven 45 extends from the second to the sixteenth station and includes those stations at which the high vacuum pump is working, the stations at which the metallic charge is maintained in molten condition and the station at which the charge is flashed or vaporized. As each coated bulb passes out of the oven at the sixteenth station it is ready to be subjected to the cooling operation which begins at the seventeenth station. The oven 45 terminates at the sixteenth station and in leaving that station each bulb supporting unit moves into range of a curved perforated duct 80 from which cooling air is blown against the bulb in its movement from the sixteenth to the twenty-third station. The operator is free to remove the coated bulb from the bulb-supporting unit at any time between the 23rd and the first station. In the regular practice of our process the completed bulb will be removed and a new bulb presented to the unit while the latter remains at rest at the 24th station.

A preferred construction of adjustable electrode is shown in Fig. 2 and a somewhat different form of electrode is shown in Fig. 6. In the latter instance the electrodes 81 are not in themselves adjustable but are provided at their upper ends with longitudinal bores in which are adjustably received the vertical rods 82 each of which is provided with an adjustable collar 83. Each rod has at its upper end a holder in the form of a sleeve 84 in which is inserted one of the downwardly extending legs of a boat 85 similar in its general construction to the boat already described and as illustrated in Figs. 3 and 4. The rods 82 may be adjusted vertically in the electrodes to locate the boat 85 at the desired level in the bulb. The collars 83 adjustably support a shield 86 comprising a disk of refractory material at the desired level in the neck of the bulb for the purpose of limiting the lower boundary of the metallic coating 87 which is to be applied to the bulb. Either form of electrode, providing as it does the necessary flexibility of adjustment, is entirely satisfactory. The unit illustrated in

Fig. 6 is shown as provided with a refractory shield in the shape of a disk 88 perforated to permit passage of the electrodes and the exhaust tube 27 and spaced above the surface of the sealing disk 16 so as to still further shield that element from heat developed at the boat 85.

In Figs. 8, 9 and 10 are illustrated illustrative forms of electrodes for supporting two boats within a bulb to be coated. The use of two boats is a convenience in coating bulbs of large size or of special shape as already explained. In Fig. 8 three electrodes are provided, the outer electrodes passing upwardly through the sealing disk 16 of the unit and supporting the boat 91 between their upper ends. A third and shorter electrode 92 extends upwardly through the sealing disk 16 and supports at its upper end a second boat 93 which is connected to an adjustable collar on the left hand electrode 90. The boats 90 and 93 may be independently adjusted as to height and the metallic contents thereof may be flashed independently and successively by current supplied through the three wire circuit as shown. In this instance it will be seen that the two boats are included in circuits which may be operated independently and of which the electrode 90 is a common element.

In Fig. 9 two electrodes 96 are shown as passing upwardly through the sealing disk 16. These carry at their upper end a boat 97 and are provided with a pair of adjustable collars 98 carrying a second boat 99. As before, the boats 97 and 98 may be independently adjusted as to height. In this instance they are included in parallel in a single circuit and must accordingly be flashed simultaneously.

In Fig. 10 an electrode construction is shown in which two boats 100 and 101 are arranged in series. An electrode 102 passing upwardly through the sealing disk 16 is provided at its upper end with a socket for one leg of the boat 100. A short electrode 103 passing up through the sealing disk 16 is provided in its upper end with a socket for one leg of the boat 101. The other leg of the boat 101 and one leg of the boat 100 are connected in series through an electrode member 105. In this arrangement also the bulbs may be adjusted as to vertical height and are arranged to be flashed simultaneously.

From the foregoing description of the particular apparatus herein illustrated it will be apparent that the process of our invention involves the essential steps of sealing each bulb with a cooled medium while the bulb contains a charge of fusible metal, exhausting and heating the bulb, melting the metal charge and maintaining it in molten condition in the exhausted bulb and finally flashing or vaporizing the molten metal. These steps will now be summarized as they are carried out with the assistance of the illustrated apparatus. It may be assumed that the ring 10 is at rest with the oven 45 in heated condition and cooling water circulating through the cooling system and one of the bulb-holding units positioned at the 24th station of the diagram of Fig. 7. The operator has thus the opportunity to place a pellet of silver or other metal in the boat of this unit, and to place an inverted bulb over the electrodes, sealing its lower end upon the rubber disk 16 as suggested in Fig. 2. The ring is then advanced in counterclockwise direction and the unit carried to station No. 1 where the rough vacuum pumps start the work of exhausting the bulb. In the next step the unit is carried to station No. 2 where it enters the receiving end of

the annular oven 45. In the successive steps of the ring the unit is advanced to stations No. 3, to station No. 4 where the leak detector operates and to stations Nos. 5, 6 and 7 where the high vacuum pump begins to operate. In its movement to these stations and to the ensuing stations, the bulb is gradually brought to a high temperature by the oven and a high degree of evacuation is reached within the bulb. At station No. 13 the metal charge in the boat is reduced to molten condition, and maintained in this condition while the high vacuum pump is still at work and is effective to withdraw any oxygen or other gas evolved by the molten metal. At station No. 13 the flashing operation occurs in a controlled interval of time and at station No. 16 the bulb passes from the oven and the vacuum tube of that unit is sealed. From station No. 16 around to station 23 the bulb is gradually cooled and at the latter station atmospheric pressure is admitted to the bulb and thereafter it may be removed from the apparatus.

While we have referred to the flashing operation as occurring at the thirteenth station it is a fact that some vaporization of the metal charge may take place before this station is reached but this does not interfere with the application of a complete metallic coating in the flashing operation as above outlined.

It will be understood that while the apparatus above described is well adapted for use in carrying out the process of our invention, other forms of apparatus may be used with good advantage within the scope of our invention. Our invention includes within its scope the novel electric lamp bulb provided with fine and coarse crystalline areas in its reflecting coating, herein shown as produced by the process of our invention.

Having thus described our invention, what we claim as new and desire to secure by Letters Patent of the United States is:

1. The process of metal-coating bulbs or the like, which comprises closing the bulb with a solid compressible seal, moving the bulb through a heated zone, simultaneously cooling the seal and thereby preventing vaporization from the seal into the bulb, substantially exhausting the bulb, and then locally heating a metal charge within the bulb to the point of vaporization.

2. The process of metal coating lamp bulbs, which consists in inverting a bulb over a charge of metal, sealing the neck of the bulb with a solid compressible seal, supporting the seal upon a flat water-cooled surface, and meanwhile raising the metal charge to its vaporizing temperature.

3. The process of metal coating lamp bulbs which includes the steps of inverting a bulb over a charge of metal, cushioning the end of the neck of the bulb upon a resilient cushion, supporting the cushion upon a flat water-cooled surface and thus preventing vaporization from the cushion into the bulb, and meanwhile heating the charge to the point of vaporization.

4. The process of metal coating lamp bulbs, which includes the steps of inverting a bulb over a charge of metal, cushioning the end of the neck of the bulb upon a resilient cushion, sealing the neck with a projecting part of the cushion, water-cooling the cushion and seal to prevent vaporization from them into the bulb, and meanwhile heating the charge and vaporizing it.

5. The process of metal coating lamp bulbs, which includes the steps of inverting a bulb over a charge of metal, sealing the neck of the bulb with a solid compressible seal, maintaining a sub-

stantial body of water adjacent to the seal for cooling the same and thus preventing vaporization therefrom into the bulb, and meantime heating the metal charge to the vaporizing point.

6. The process of metal coating lamp bulbs, which includes the steps of inverting a bulb over a metal charge carried at the top of an elongated support, sealing the neck of the bulb about the support by a solid compressible seal, water-cooling the seal and the lower end of the support, and meantime heating the metal charge to the vaporizing point while vaporization from the seal and

support into the bulb is prevented by the said water cooling thereof.

7. The process of metal coating lamp bulbs, which includes the step of vaporizing a charge of fusible metal while confined within the bulb by walls which are inclined to direct most of the vapor of the charge toward the bowl end of the bulb and are apertured to direct a minor portion of the vapor of the charge toward the neck portion of the bulb.
